UNITED STATES PATENT OFFICE.

HARRY A. ORME, OF WESLEY HEIGHTS, DISTRICT OF COLUMBIA.

AERODROME.

No. 926,593.

Specification of Letters Patent. Patented June 29, 1909.

Application filed January 26, 1909. Serial No. 474,280.

To all whom it may concern:

Be it known that I, HARRY A. ORME, a citizen of the United States, residing at Beechwood, Wesley Heights, in the District 5 of Columbia, have invented certain new and useful Improvements in Aerodromes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to the class of aerial navigation but more particularly to an aerodrome, and my invention has for its object to provide an aerodrome having three planes arranged one above the other, the 20 highest, or what will be hereinafter termed the controlling plane, being employed solely as a steadyng and guiding means, and may also be employed in cases of emergency in 25 order to prevent the aerodrome from losing its equilibrium so that in descending the aeroplane will maintain its normal relative position.

A further object of my invention is to 30 provide a novel construction in the front or fore planes, and a further object of my invention is to provide a novel construction in the rear vertical rudder planes.

With all these objects in view my invention 35 consists in the novel construction and arrangement of the controlling plane.

My invention also consists in the novel 40 construction and arrangement of the front or fore planes.

My invention also consists in the novel 45 construction and arrangement of the rear vertical rudder planes; and my invention also consists in certain other novel features of construction and in combinations of parts, all of which will be first fully described and afterward specifically pointed out in the appended claims.

Referring to the accompanying drawing: Figure 1 is a side elevation of an aerodrome constructed in accordance with my invention. Fig. 2 is a top plan view of the same. Fig. 3 is a detail fragmentary sectional view through the controlling plane. Fig. 4 is a similar view showing the same in a different position. Fig. 5 is a fragmentary view 55 showing the post and arrangement of parts of the controlling-plane. Fig. 6 is a plan view

of one of the adjustable tips of the controlling-plane. Fig. 7 is a side elevation of the same. Fig. 8 is a rear elevation of the front or fore planes. Fig. 9 is an end elevation of the same. Fig. 10 is a transverse horizontal sectional view through the front or fore planes. Fig. 11 is an end elevation of the rudder planes. Fig. 12 is a side elevation of the same. Fig. 13 is an end elevation of the rudder planes 65 showing the vertical planes distended and Fig. 14 is a top plan view of the rudder planes.

Like characters of reference indicate the same parts throughout the several figures in which;

1 indicates the aerodrome which comprises the two main planes 2 and 3, the upper plane 2 being of a length equal to that of the lower plane 3 but slightly wider as shown in Fig. 1 and in dotted lines in Fig. 2. Suitable braces or stanchions 4 are employed between the two planes 2 and 3 in order to securely tie and brace same in their proper relative positions; while the motive power (not shown) is preferably arranged on the lower plane 3 at the center thereof and at a point which will balance the machine while the propelling mechanism (not shown) is arranged preferably behind the lower plane 3 in any convenient manner.

5 indicates the front or fore planes which as shown in Figs. 8, 9 and 10 are supported on the uprights 6 by means of straps 7 (Figs. 8 and 10), it being of course understood that all of the planes of the machine are covered 90 with a suitable light and strong covering 8 as shown in Figs. 9 and 10. The front or fore planes 5 are each formed of two sections 9 and 10, said sections being hinged together at 11 and also hinged to uprights 12 arranged 95 at each end of the front or fore planes 5.

13 indicates a central rod or shaft arranged about midway between the two front or fore planes 5. Carried on said rod 13 are preferably three longitudinal arms 14, said arms 14 being formed of two sections 15 and 16, said sections being hinged together at 17 having their contiguous ends 18 cut away at 19 in order to embrace the central rod 13 as clearly shown in Figs. 9 and 10. Referring, however, to Fig. 10 it will be seen that a pin 20 carried on the hinge 17 passes through the central rod 13 in such manner that rotation of the rod 13 is imparted to the arms 14. Carried on the rod 13 are two operating arms 21 and 22, from which operating arms wires 23 and 24 lead through blocks 25 arranged on

the transverse piece 26 directly under the front or fore planes 5. These operating wires 23 and 24 pass rearwardly so as to be operated by the aviator, and by means of these wires the front or fore planes 5 can be thrown into position shown in dotted lines in Fig. 9, or can be thrown in the reverse direction as is of course clearly apparent.

Connecting each of the front or fore planes 10 5 with the arms 14 are a series of links 27 so arranged that upon movement of the arms 14 the planes 5 will be correspondingly moved.

It will be seen from Figs. 9 and 10 that 15 two wires 28 and 29 pass from the forward and rear edge of the lower front or fore plane 5 through blocks 30 located on the transverse piece 26, said wires leading rearwardly to be operated by the aviator. By means of these 20 wires both the front or fore planes 5 can be thrown into position shown in Fig. 10 so that in case of emergency or in descending the planes can be made to assume the position shown in Fig. 10, thus offering a greater air 25 resistance and checking the descent of the aerodrome. As is of course apparent that in order to cause the aerodrome to descend the front or fore planes 5 are thrown into position shown in dotted lines in Fig. 9, while the 30 reverse position will cause the aerodrome to ascend.

As will appear from Fig. 1 suitable braces 31 are employed in order to secure and hold the fore planes 5 in proper relative position, 35 while skids or runners 32 are employed for the purpose of receiving the shock of descending and also for the purpose of supporting the aerodrome on a launching track.

Referring now to Figs. 11, 12, 13 and 14 40 which illustrate the vertical rudder planes 33 and 34 it will be seen that they are connected together at their upper ends by means of a small plane 35, the vertical planes 33 and 34 being hinged thereto at 36. The lower ends 45 of each of the planes 33 and 34 are provided with a pin 37, the pins 37 operating in slots 38 located in a curved strap 39, said strap 39 being pivoted on a longitudinal piece 40 at the point 41, while the top plane 35 is pivoted 50 to the longitudinal piece 42 at the point 43. An operating rod 44 (Fig. 14) connected to the curved strap 39 swings the vertical rudder planes 33 and 34 on the pivots 41 and 43 as is of course obvious. As will appear 55 from Figs. 11 and 12 the vertical rudder planes 33 and 34 are connected together at their lower ends by means of a spiral spring 45, said spring normally holding the planes 45 in position shown in Fig. 11. Connected to 60 the pins 37 on the lower end of each of the planes 33 and 34 is an operating wire 46, the wires 46 running from blocks 47 and leading forwardly for convenient manipulation of the aviator; and by means of these wires 46 the 65 vertical rudder planes 33 and 34 can be

thrown into position shown in Fig. 12 so that in case of emergency or in descending greater air resistance is imparted in such manner that the rudder planes 33 and 34 while normally acting in the capacity of the rudder 70 become when in position shown in Fig. 12 an element for offering resistance while the machine is descending.

Referring now to the controlling plane 48 it will be seen that this plane is arranged 75 above the plane 2 and is preferably carried on a post or stanchion 49. The controlling plane 48 is composed of an upper series of arms or braces 50 similar to the arms or braces of a parasol; while a series of similar 80 braces 51 are arranged on the post or stanchion 49 directly under the upper series of braces 50, each of said series of braces 50 and 51 being pivoted at 52 and 53 in such manner that they can be swung into position 85 shown in Fig. 4 or into position shown in dotted lines in Fig. 3. Both the upper and lower series of braces 50 and 51 are provided with a suitable covering 54, while the covering 90 around the outer edge of the controlling plane upon the upper series of arms 50 is preferably made of some resilient material 55, such as thin sheet rubber, in such manner that the same will stretch when the arms 95 are in position shown in Fig. 4. Carried on the end of each of the lower arms 51 is a guidepiece or tip 56, said guide piece or tip 56 being provided in each side thereof with a longitudinal slot 57; while the end of each of the upper arms 50 is provided with a plate 100 58 having two lugs or projections 59 thereon, which lugs or projections 59 operate within the slots 57 as clearly shown in Fig. 7. Connecting each of the lower arms 51 is a rim 60 and to this rim the covering 54 on the upper 105 arms 50 is substantially secured. Connected to each of the tips 56 of the lower arms 51 is a wire 61, said wire leading inwardly and is connected to the central post or stanchion 49 by means of coil springs 62, 110 the normal position of which is that shown in Fig. 3, and by reason of this construction the springs 62 and wires 61 normally hold the arms 50 and 51 of the controlling plane in position shown in Fig. 3.

Referring now to Fig. 1 it will be seen that a wire is connected to each end or tip of the lower arms 51 of the controlling plane, and in order to set forth clearly this construction reference will be had to Fig. 2 in which the 115 different tips of the controlling plane are designated by letters *a*, *b*, *c*, *d*, *e*, *f* and *g*, *a*, *b* and *c* being controlled separately and independently from the tips *d*, *e* and *f*. Referring now to Fig. 1 it will be seen that wires *a'*, *b'* and *c'* lead to the tips *a*, *b* and *c*, while a similar arrangement of wires lead to the tips *d*, *e* and *f*. By means of this construction therefore one series of tips *a*, *b* and *c* for instance 125 can be carried down into position shown in 130

dotted lines in Fig. 3, and the other series of tips *d*, *e* and *f* can be allowed to remain in their normal position as shown in full lines in Fig. 3. By lowering either series of tips the 5 aerodrome is caused to turn, as it has been found from experience that a short turn cannot be accomplished solely by means of vertical rudder planes.

Referring again to Fig. 1 it will be seen 10 that a series of wires 63 are connected to each of the tips *a*, *b*, *c*, *d*, *e*, *f* and *g*. Said series of wires leading to a convenient position to the aviator makes it possible to lower all of the tips of the controlling plane into position 15 shown in Fig. 4 so that in the case of emergency or in descending the controlling plane can be caused to assume this form in order to offer greater air resistance. By this construction of wires the controlling plane can 20 be altered to assume the position shown in Fig. 4, or merely one side of the tips can be carried down in order to cause the controlling plane to assume the position shown in dotted lines in Fig. 3.

25 Referring now to Fig. 1 it will be seen that the controlling plane is of a particular form, the forward arms thereof being very short while the side and rear arms thereof are considerably longer. By means of this construction the tendency of the controlling plane to buckle in an upward direction is entirely obviated for the reason that were the forward arms as long as the side or after arms the air pressure under the forward arms 35 would tend to raise the same and throw them back, which would throw an undue strain upon the operating wires and disturb the equilibrium of the machine.

Having thus fully described my invention 40 its operation is as follows: In order to cause the aerodrome to ascend the front or fore planes 5 are thrown into the reverse position from that shown in dotted lines in Fig. 9; while in order to cause the aerodrome to 45 descend the front or fore planes 5 are thrown into position shown in dotted lines in Fig. 9. In making a slight turn the vertical rudder planes 33 and 34 are swung by means of the operating rod 44 on their pivots 41 and 43, 50 but in order to make a sharp turn one series of tips *a*, *b*, *c* or *d*, *e* and *f* is carried down into position shown in dotted lines in Fig. 3. If it is desired to turn to the left considering the machine as shown in Fig. 2 the tips *a*, *b* and *c* 55 are depressed; while if it is desired to turn to the right the tips *d*, *e* and *f* are depressed; while if it is desired to increase the air resistance as in an emergency or in descending all of the arms of the controlling plane are de- 60 pressed into position shown in Fig. 4 while the front or fore planes are thrown in position shown in Fig. 10 and the vertical rudder planes are thrown into position shown in Fig. 12, thus balancing the machine, increas-

ing the air resistance thereof and causing it 65 to maintain its proper equilibrium.

It is of course apparent that slight variations may be made in the construction as shown and described, and it is of course obvious that any operative motive power and propelling 70 mechanism can be employed in connection with my aerodrome, and I claim no specific motive power or means of propelling, but

What I do claim and desire to secure by Letters Patent of the United States is,

75 1. An aerodrome comprising three superposed planes, the highest or controlling plane comprising a series of radial ribs, means for lowering the tips of said ribs simultaneously and means for lowering the tips independently, a plurality of forward planes, and means for lowering the forward and rear edges of the same, a plurality of rear vertical planes, a horizontal plane connecting said vertical planes together and means for separating the lower portions of said vertical planes.

80 2. An aerodrome comprising a controlling plane in combination with suitable supporting planes, said controlling plane comprising a series of radial ribs, means for lowering the tips of said ribs simultaneously and means for lowering certain groups of said tips independently.

85 3. In an aerodrome the combination with suitable supporting planes, of a controlling plane arranged above said supporting planes, means for lowering the entire outer edge of said controlling plane simultaneously and means for lowering a portion of the outer 90 edge independently of the remaining portion of the outer edge of the controlling plane.

95 4. In an aerodrome the combination with suitable supporting planes, of a controlling plane arranged above said supporting planes 100 and means for lowering a portion of the outer edge of the controlling plane independently of the remaining portion of the outer edge of the controlling plane.

105 5. An aerodrome comprising three planes arranged one above the other, means for lowering a portion of the edge of the highest plane independently of the remaining portion of the edge of the highest plane.

110 6. An aerodrome comprising three planes arranged one above the other and means for operating the highest plane to control the aerodrome.

115 7. An aerodrome comprising suitable supporting planes, a plurality of forward horizontal planes and means for lowering the forward and rear edges of said last mentioned planes simultaneously.

120 8. An aerodrome comprising a suitable supporting plane, a forward plane horizontally pivoted and means for lowering its forward and rear edge simultaneously.

125 9. An aerodrome comprising a suitable

supporting plane, a plurality of vertical rear planes, a horizontal plane connecting the upper ends of said vertical planes and means for separating the lower ends of said vertical planes.

10. An aerodrome comprising a suitable supporting plane, two pivoted vertical steering planes and means for separating the lower ends of said pivoted vertical steering planes.

10 11. An aerodrome comprising a controlling plane and a suitable supporting plane, said controlling plane comprising a series of upper radial ribs, and a series of lower radial ribs and a sliding connection between the ends of said upper radial ribs and said lower radial ribs.

15 12. An aerodrome comprising a plane, a series of upper ribs, a series of lower ribs for said plane and a sliding connection between the ends of one set of ribs and the other set.

13. An aerodrome comprising a plane, a series of upper ribs, a series of lower ribs for said plane, and means for slidably connecting the ends of one set of ribs to the other set.

14. An aerodrome comprising a plane, a series of upper ribs, a series of lower ribs for said plane, tips on one set of ribs and means for effecting a sliding connection between the said tips and the ends of the other set of ribs.

15. A plane for an aerodrome comprising two sets of ribs, a metallic tip on the end of each rib of one set, and means for effecting a sliding connection between the tips of one set of ribs and the ends of the other set.

In testimony whereof, I affix my signature, 35
in presence of two witnesses.

HARRY A. ORME.

Witnesses:

C. M. FORREST,
C. HUGH DUFFY.
